DESIGN FOR A DRESS

Anne Rebhuhn, New York, N. Y.

Application December 18, 1939, Serial No. 88,969

Term of patent 3½ years

To all whom it may concern:

Be it known that I, Anne Rebhuhn, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design, and

Fig. 2 is the rear view thereof on a reduced scale.

The design is characterized by the combination

on the specific dress disclosed of the short strap extending from the shoulder to the horizontal ruffle across the front of the dress at the neckline, the specific front girdle, and the two flat, self-material, stitched folds extending completely around the skirt, said stitched folds giving the appearance of superimposed bands holding the skirt in balloon-like folds, as shown.

I claim:

The ornamental design for a dress, substantially as shown and described.

ANNE REBHUHN.
